IRONING MACHINE

Andrew O. McCollum, Detroit, Mich., assignor to
 Hydraulic Brake Company, Detroit, Mich., a
 corporation of California

Application June 23, 1934, Serial No. 732,129

14 Claims.

(Cl. 38—25)

This invention relates to ironing machines and more particularly to ironing machines for domestic use.

The invention comprehends an ironing machine including cooperative ironing elements and fluid pressure means for actuating one of the ironing elements and for retaining the other ironing element in any one of a plurality of operative positions. The fluid pressure means includes a fluid reservoir, a pressure producing element supplied therefrom, and fluid pressure actuated motors actuated by the pressure producing elements, one of the motors is arranged to actuate means for retaining one of the ironing elements in one or 10 more operative positions and the other motors are arranged to actuate the other ironing element to create an ironing pressure between the elements.

An object of the invention is to provide an ironing machine including cooperative ironing elements, fluid pressure means for actuating one of the elements, and means actuated by the fluid pressure means for retaining the other ironing element in one or more operative positions.

Another object of the invention is to provide an ironing machine including cooperative ironing elements, one movable manually into operative position, means for retaining the manually movable element in any one of a plurality of operative positions, and fluid pressure means for actuating 30 the other ironing element including means for actuating the retaining means.

A feature of the invention is a pair of cooperative ironing elements, any one movable manually into one of a plurality of operative positions, and 35 fluid pressure means for moving the other ironing element to create an ironing pressure between the elements including means for actuating the retaining means prior to movement of the ironing element to create an ironing pressure.

40 Other objects and features of the invention will appear from the following description taken in connection with the drawings forming a part of this specification, and in which,—

Figure 1 is a cross-sectional view of an ironing machine embodying the invention;

Figure 2 is a fragmentary view in section, illustrating means for retaining the head in any one of a plurality of operative positions.

Figure 3 is a longitudinal sectional view partly broken away;

Figure 4 is a top plan view of the buck support;

Figure 5 is a side elevation, partly in section and partly broken away, illustrating the assembly

of the fluid pressure means, the buck support, and the buck;

Figure 6 is an enlarged sectional view of one of the motors and associated guide for the buck;

Figure 7 is a top plan view of the pressure producing device;

Figure 8 is a sectional view substantially on line 8—8, Figure 7;

Figure 9 is a diagrammatical illustration of the electric circuit for the machine;

Figure 10 is an enlarged sectional view substantially on line 10—10, Figure 7, of the pressure producing device; and

Figure 11 is an enlarged sectional view substantially on line 11—11, Figure 7, of the valve mechanism forming a part of the pressure producing device.

Referring to the drawings for more specific details of the invention, 10 represents a frame including a rectangular casting having a pan 12 at one end and a hollow vertical column 14 at its other end. A sleeve 16, bolted or otherwise secured to the frame concentrically of the column 14, has fitted therein a column 18 constituting the main support of the frame; and secured to the frame are corresponding legs 20 for cooperation with the column 18.

An apron 22 is suitably secured to the frame to conceal parts of the operating mechanism to be hereinafter described. A top 24 supported on the frame has an opening for the reception of the column 14, and a frusto-conical portion 26 extending upwardly immediately above the pan 12, and this frusto-conical portion has an opening in its top, the purpose of which will herein-after appear. The top also has an apron 28 effectively concealing the frame.

A fluid pressure producing device 30 mounted in the pan 12 includes a casting comprising a reservoir 32 having therein a spring-pressed piston 34. As shown, the piston is formed with a concentric sleeve 36 extending forward and rearward of the head of the piston. This sleeve has a circumferential flange 38 and an internally threaded portion 40. A leak-proof cup 42 seated on the head of the piston is retained against displacement by the flange 38, and a hollow piston rod 44 threaded in the sleeve is closed as by a removable plug 46.

A cover plate 48, retained in the open end of the reservoir by a split ring 50 seated in a circumferential groove in the wall of the reservoir, has an opening for the reception of the piston rod 44, and a coil spring 52 interposed between the cover plate 48 and the back of the piston 34 urges the

piston toward the bottom of the reservoir so as to place the fluid in the reservoir under pressure. When it is desired to fill the reservoir, the plug 46 is removed and the piston is retracted by a 5 suitable tool which may be fitted on the outer end of the rod 44, so that the reservoir may be filled through the rod 44.

A compound cylinder 54 is formed at the bottom of the reservoir. This cylinder includes a 10 low pressure chamber 56 and a high pressure chamber 58. The low pressure chamber 56 has ports 60 and 62 providing communications between the low pressure chamber and the reservoir, and the high pressure chamber has a 15 charge port 64 controlled by a check valve 66.

The valve 66 includes a coupling 68 secured in the discharge port 64, and suitably secured to the other end of the coupling is a pipe section 70 providing a valve chamber 72. The coupling is 20 closed at one end as at 74 and is provided with a transverse bore 76. The closed end has a reduced portion 78 on which is fitted a flexible sleeve 80 which provides for the flow of fluid in one direction only.

25 A reciprocable piston 82 in the chambers 56 and 58 is retained against displacement by a transversely split ring 84 seated in a circumferential groove in the wall of the low pressure chamber. This piston has heads 86 and 88 spaced apart by a sleeve 90. The head 86 is fitted in the chamber 56 and the head 88 is fitted in the chamber 58. The skirt of the piston has a portion of reduced cross-sectional area providing, in conjunction with the wall of the chamber 56, an 30 annular chamber 92 communicating by way of the port 60 with the reservoir 32, and a leak-proof cup 94 is fitted on the skirt between radial flanges.

The head 86 of the piston has a plurality of 40 ports or passages 96 providing communications between the annular chamber 92 and that portion of the cylinder forward of the head 86. A collapsible leak-proof cup 98 loosely fitted in a circumferential groove in the piston controls the 45 flow of fluid through the ports or passages 96. This cup is normally held on its seat by a relatively light spring 100 interposed between the cup and a stop 102 carried by the piston.

A plug 104 suitably secured in the skirt of the 50 piston provides, in conjunction with the skirt, a chamber 106 having a port 108, providing a communication between the chamber 106 and the annular chamber 92, and a plurality of ports 110, providing communications between the chamber 55 106 and that portion of the cylinder forward of the head 86.

The head 88 of the piston has a plurality of 60 ports 112 providing communications between the chambers 56 and 58, and a collapsible leak-proof cup 114, seated on the head 88 and held against displacement by a flange 116, controls the flow of fluid through the ports 112; and a spring 118 interposed between the flange 116 and the head 65 of the cylinder serves to return the piston to its retracted position. The head 88 has an opening 120 providing a restricted communication between the sleeve 90 and the chamber 58.

A reciprocable piston 122 in the sleeve 90 has 70 connected thereto a valve 124 urged by a spring 126 interposed between the valve and the plug 104 to seat on a cushioned washer 128 and to close the passages 110. A leak-proof cup 130 on the head of the piston 122 is held against displacement by a spring 132 interposed between 75 the cup and the back of the head 88.

The plug 104 in the skirt of the piston has a recess 134 receiving one end of a thrust rod 136, the other end of which is pivotally connected to an arm 138 keyed or otherwise secured to a shaft 140 journaled in a bearing 142 on the frame 10. 5 An operating lever 144 is suitably secured to the shaft, and adjustably attached to the operating lever is an extension 146 having upon its free end a hand grip or knob 148. By applying force to the lever the shaft may be moved through an angle and this movement is transmitted through the arm 138 and thrust rod 136 to the piston to move the piston on its compression stroke.

A valve chamber 150 at the bottom of the reservoir is provided with a port 152 providing a communication between the valve chamber 150 and the reservoir 32, and ports 154 and 156 the purpose of which will hereinafter appear. The chamber 150 has therein a valve cage 158 secured in position by a plug 160 threaded in the open end of the chamber. The valve cage has a reduced portion providing in conjunction with the valve chamber a chamber 162 communicating by way of the port 152 with the reservoir 32, and a plurality of ports 164 providing communications 20 between the chamber 162 and the interior of the valve cage. The cage also has a port 166 and a valve seat 168.

A leak-proof cup 170 is seated on the valve cage. This cup has an opening 172 of smaller diameter than the diameter of the port 166 so that the periphery defining the opening 172 overhangs the port 166, the object of which will hereinafter appear. A leak-proof cup 174 is seated on the head of the valve chamber 150 and a spring interposed between the cups 170 and 174 retains these cups against displacement.

A valve 176 has a cylindrical portion 178 adapted to fit in the port 166 and a frusto-conical portion 180 adapted to engage the seat 168 when the valve is in closed position. The inner periphery of the cup 170 defining the opening 172 abuts the cylindrical portion 178 of the valve and seals the valve. The valve has a stem 182 which extends through the head of the chamber, and suitably secured on this valve stem is a collar 184, and sleeved on the stem between the head of the valve chamber and the collar 184 is a coil spring 186 normally urging the valve to its seat. The valve stem 182 is suitably supported, and the free end of the stem engages an arm 188 on a sleeve 190 suitably secured to the shaft 140.

A cylinder 192 is formed in the casting beneath the cylinder 58. This cylinder communicates by way of the port 156 with the valve chamber 150, and a reciprocable piston 194 in the chamber 192 has thereon a leak-proof cup 196 and a thrust pin 198, the purpose of which will hereinafter appear.

A buck support 200 suitably mounted on the reservoir 32 includes an elongated receptacle having mounted in its respective ends motor cylinders 202 and 204 provided with oppositely disposed guides 206 and 208. The cylinders are connected respectively by conduits 210 and 212 to a coupling 214, and the coupling is connected by conduits 216 and 218 to the valve chamber 72 communicating with the discharge port 64 of the high pressure chamber 58 and to the port 70 154 in the valve chamber 150, respectively.

Reciprocable pistons 220 in the respective cylinders of the motors 202 and 204 each include a head 222 provided with a concentric extension 224 having a reduced portion for the recep- 75

tion of a leak-proof cup 226. Each of the pistons has an axial passage 228 communicating with a diametral passage 230 in the extension, and threaded in the axial passage 228 is a bleeder screw 232, and a cap 234 threaded on the pistons encloses the bleeder screw.

A buck 236 has on its ironing face a pad 238 over which is secured a suitable cover 240. On the back of this buck are pressure plates 242 engaging the caps 234 on the pistons 220. The buck also has formed on its back sleeves 244 received by the guides 206 and 208. Rods 246 suitably secured in the bottom of the buck support are received by the sleeves 244. The rods have thereon heads 248 and coil springs 250 interposed between the heads and a retaining ring 252 seated in circumferential grooves in the walls of the sleeves.

An ironing head 254 adaptable for cooperation with the buck is pivotally connected to corresponding oppositely disposed horns 256 formed on a hollow arm 258 having a flared end 260 telescoping a spherical portion 262 on the column 14, and an internal web 264 having a lateral arm 266 pivoted to the spherical portion and extending beyond the pivot downwards into the column 14. The arm 258 has attached thereto a rod having on its free end a knob or hand grip 265 by which the head may be moved into operative position. The arm 266 has suitably attached thereto corresponding ends of springs 268, the other ends of which are attached to adjusting screws 270. These springs serve to swing the arm upward and thereby return the head to inoperative position.

A drum segment 272 is suitably pivoted on the frame 10 and connected as by a link 274 to the end of the arm 266. A lever 276, also pivoted on the frame, has a frictional face 278 adaptable for cooperation with the drum segment 272. This lever is actuated by the thrust pin 198 carried by the piston 194, and is retained in engagement with the thrust pin by a spring 280 connected between the lever and the frame. The lever 276 carries an adjusting screw 282 for regulating the throw of the lever.

A lever 284 pivoted on the frame has a lug 286 adaptable to engage a cam formed on the arm 138 and is held in engagement therewith by a spring 288 connected between the lever 284 and the frame. This lever cooperates with the cam surface on the arm 138 to retain the operating lever 144 in neutral position.

A lever 290 suitably pivoted on the frame 10 has a lug 292 adapted to ride on a sleeve 190 on the shaft 140, and a spring 294 connected between the lever 290 and the frame normally holds the lug 292 in engagement with the sleeve. This lever has pivoted thereto an arm 296 connected by a spring 298 to the lever 290. When the lever 276 is in engagement with the drum 272, the arm 296 engages the flange on the drum segment and retards movement of the drum in the opposite direction.

When the lever 144 is actuated to relieve the pressure on the compression device, a pin or stud 300 carried by the arm 138 engages the lug 292 and trips the lever 290, resulting in disengaging the arm 296 from the flange of the drum 272, whereupon the spring 298 trips the arm 296 and frees the drum 272 so that springs 268 may effectively return the head to inoperative position. When the head is returned to inoperative position, the drum segment 272 is moved through an arc to engage the pin or stud 300 carried by

the arm 138 to lock the operating lever against movement.

A fluid pressure switch 302 secured in the coupling 214 is connected in a circuit 304 including a lamp 306 housed in the arm 256 back of an opening having therein a colored glass 306. The circuit 304 is tapped off of a circuit 310 including a heating element 312, suitably arranged in the ironing head 254, and a rheostat 314. The circuit 310 may be connected to any suitable source of electrical supply.

In operation, assuming that the fluid pressure operated system is filled with fluid, that the circuit 310 is connected to a suitable source of electrical supply, that the ironing head 254 is in elevated or inoperative position, and that the buck is in the position of rest wherein the pistons 220 of the motor cylinders 202 and 204 are in fully retracted position and the buck is held against the pistons 220 by the springs 250, under these conditions, the operator places the work upon the buck and lowers the head 254 into operative position by the hand grip 265, which position varies according to the thickness of the work.

Upon moving the head into operative position, the arm 266 is moved through an angle. This movement of the arm 266 places the return spring 268 under tension and transmits force through the link 274 to the drum segment 272 to move the drum segment in position for cooperation with the lever 276. As the drum segment moves into position for cooperation with the lever 276, the finger 296 on the lever 290 frictionally engages the flange of the drum segment and resists return movement of the drum segment.

After moving the head into operative position, the operator applies force to the lever 144 by pressing downward on the hand grip 148. This movement of the lever 144 rocks the shaft 140 and moves the arm 138 thereon through an angle. This movement of the arm 138 causes the cam on the arm to ride over the lug 286 on the lever 284, and to transmit force through the thrust pin 196 to move the piston 82 on its compression stroke.

During the initial movement of the piston 82 on its compression stroke, the leak-proof cup 98 on the head 86 of the piston covers the port 62 and the fluid in the low pressure chamber 56 is displaced therefrom through the ports 112 in the head 86 of the piston, past the leak-proof cup 114 into the high pressure chamber 58, thence through port 64, past the check valve 66, through conduit 218, coupling 214 and conduits 210 and 212 into the motor cylinders 202 and 204, also through conduit 216, valve chamber 150, thence through port 156 into cylinder 192. Because of the difference in the value of the spring 280 and the springs 250, the piston 194 is actuated in advance of the motor pistons 220, resulting in actuation of the lever 276 to engage the drum segment 272 to retain the head 254 against movement. Further increase in pressure results in actuation of the pistons 220 in the motor cylinders 202 and 204, and the consequent movement of the buck 236 against the head.

This movement of the buck is the result of the displacement of fluid due to the initial movement of the piston 82, and further movement of the piston 82 creates sufficient pressure between the buck and the ironing head to effectively iron the work. The buck is moved against the resistance of the springs 250, resulting in compressing the

springs between the heads on the rods 246 and the retaining rings 252 in the cylinders 244.

As the piston 82 is moved upon its compression stroke, the cam on the arm 138 rides over the lug or stop 286 on the lever 284 and displaces the lever 284, the object of which will hereinafter appear. Upon further movement of the piston 82 a predetermined pressure is obtained, whereupon the piston 122 is actuated by fluid under pressure in the low pressure chamber 56, resulting in tripping the valve 124 and thereby rendering the head 86 of the piston ineffective for producing pressure, the fluid forward of the head 86 being returned to the reservoir by way of the ports 110, chamber 106, port 108, chamber 92, and ports 60, as the piston proceeds on its compression stroke, the fluid under pressure in the chamber 58 operating against the piston 122 to retain the valve 124 open.

20 This transition of pressure occurs over a relatively wide range depending entirely upon the relation of the area of the piston 122 to the area of the valve 124. Because of the restricted opening 120 providing a communication between the chamber 58 and the sleeve 90, sudden movements of the piston 82 on its compression stroke will not cause actuation of the valve 124.

When the pressure between the ironing elements reaches a predetermined degree, the fluid 30 under pressure in the system actuates the fluid pressure switch 302 to close the circuit 304 resulting in lighting the lamp 306. This gives a visual indication that the required ironing pressure between the ironing elements has been attained.

35 Upon releasing the applied force, the check valve 66 closes to maintain the pressure at a predetermined degree, and after maintaining the pressure for a sufficient period of time to effectively iron the work, the operator raises the lever 144. This movement of the lever 144 is transmitted to the shaft, resulting in movement of the arm 138 and retraction of the thrust pin 136. As the thrust pin is retracted, the piston 82 is returned to its normal retracted position 40 under the influence of the spring 118, and the cam on the arm 136 rides over the lug 286 on the lever 284 to retain the operating lever 144 in elevated position.

As the piston 82 returns to its retracted position, the cups 98 and 114 collapse and fluid is 50 drawn from the reservoir 32 through the ports 60, chamber 92, ports 96, past the cup 98, into the cylinder 56 forward of the piston head 86, thence through ports 112 in the piston head 86, 55 past the cup 114 and the chamber 58, filling the chambers 56 and 58 for subsequent operation. When the piston 82 is fully retracted, the cup 98 uncovers the port 62 and any surplus fluid in the cylinder is returned through this port to the reservoir.

60 Upon further movement of the operating lever 144 in the reverse direction, the shaft is moved through an angle, and this movement is transmitted through the arm 188 on the shaft to trip the valve 176, whereupon pressure on the fluid in the motor cylinders 202 and 204 and the chamber 198 is released. Upon tripping the valve 176, the fluid in the cylinders 202 and 204 and the chamber or cylinder 198 is returned therefrom to the reservoir. The fluid is returned from the cylinders 202 and 204 through the conduits 210 and 212, coupling 214, and conduit 218 to the valve chamber 150, thence past the valve 176, through port 164, chamber 162 and port 152 to the reservoir, due to the tension on the spring 250 con-

nected between the buck and the buck support. These springs also serve to retain the buck on the pistons 220 in the motor cylinders and to return the buck to its normal position.

5 Simultaneously with the return of the fluid from the motor cylinders 202 and 204 to the reservoir, fluid is returned from the chamber or cylinder 192 through the port 156 to the valve chamber 150, thence past valve 176, through port 164, chamber 162 and port 152 to the reservoir, due to the tension of spring 280 connected between the frame 10 and the lever 276, this lever being in direct engagement with the piston 194. Immediately following the tripping of the valve 176, the pin 300 on the arm 138 engages a lug 10 on the lever 290 and depresses this lever to disengage the finger 296 from the rim of the drum 272.

15 As the piston 194 returns to its retracted position, the lever 276 is moved to disengage the drum segment 262, whereupon the springs 274 become effective to return the head 254 to elevated or inoperative position. As the head returns to inoperative position, the drum segment is moved through an angle to engage the pin 300, 20 and thereby lock the lever 138 against movement to prevent operation of the fluid pressure system when the head is in elevated or inoperative position.

25 While this invention has been described in connection with certain specific embodiments, the principle involved is susceptible of numerous other applications that will readily occur to persons skilled in the art. The invention is, therefore, to be limited only as indicated by the scope 30 of the appended claims.

Having thus described the various features of the invention, what I claim is new and desire to secure by Letters Patent is:—

35 1. An ironing machine comprising cooperative ironing elements, friction means for retaining one of the elements against movement, fluid pressure actuated means for actuating the friction means, fluid pressure actuated means for moving the other element to create an ironing pressure between the elements, a pressure producing means connected to each of the fluid pressure actuated means, and means for actuating the fluid pressure producing means.

40 2. An ironing machine comprising cooperative ironing elements, friction means for retaining one of the elements in operative position, fluid pressure actuated means for moving the other element to create an ironing pressure between the elements, a pressure producing means operatively connected to the friction means, a pressure producing means connected to each of the fluid pressure actuated means, and means for actuating the fluid pressure producing means.

45 3. An ironing machine comprising cooperative ironing elements, friction means for retaining one of the elements in any one of a plurality of operative positions, fluid pressure actuated means for moving the other element to create an ironing pressure between the elements, a fluid pressure actuated means for actuating the friction means, a pressure producing means operatively connected to each of the fluid pressure actuated means, and means for actuating the fluid pressure producing means.

50 4. An ironing machine comprising cooperative ironing elements, manual means for moving one of the elements into any one of a plurality of operative positions, friction means for retaining the manually movable element in any one of a

- plurality of operative positions, means for moving the other element to create an ironing pressure between the elements, and a fluid pressure system for actuating the friction means and the moving means. 5
5. An ironing machine comprising cooperative ironing elements, means supporting one of the elements for movement into and from any one of a plurality of operative positions, friction means cooperating with the supporting means for retaining the element in any one of a plurality of operative positions, means for moving the other element to create an ironing pressure between the elements, and a fluid pressure system for actuating in sequence the friction means and the moving means. 10
10. An ironing machine comprising cooperative ironing elements, means for moving one of the elements into operative position, friction means for retaining this element in operative position, and means for moving the other element to create an ironing pressure between the elements including means for actuating the friction means. 15
15. An ironing machine comprising an ironing head, a buck for cooperation therewith, means for supporting the ironing head for movement into and from operative position, friction means cooperating with the supporting means for retaining the head in operative position, tension means cooperating with the supporting means for moving the ironing head from operative position, and hydraulic means for actuating the buck and for actuating the friction means. 20
20. An ironing machine comprising an ironing head, a buck for cooperation therewith, means supporting the head for movement into and from operative position, friction means cooperating with the supporting means for retaining the head in operative position, tension members cooperating with the supporting means for moving the head from operative position, fluid pressure actuated means for moving the buck, a fluid pressure actuated means for actuating the friction means, and means for actuating the fluid pressure actuated means. 25
25. An ironing machine comprising an ironing head, a buck for cooperation therewith, means supporting the head for movement into and from operative position, friction means cooperating with the supporting means for retaining the head in any one of a plurality of operative positions including a drum segment connected to and movable by the supporting means, friction means cooperating with the drum segment for retaining the supporting means against movement, and a fluid pressure system for actuating the buck and the friction element. 30
30. An ironing machine comprising an ironing element, a buck for cooperation therewith, means supporting the ironing element for movement into and from operative position, means tending to move this element from operative position, means for retaining this element in any one of a plurality of operative positions including a drum segment connected to and movable by the supporting means, friction means cooperating with the drum segment for retaining the supporting means against movement, a fluid pressure system for actuating the buck and the friction element, and means for actuating the fluid pressure system. 35
35. An ironing machine comprising an ironing head, a buck arranged for cooperation therewith, means supporting the head for movement into and from operative position, means tending to move the head from operative position, means for retaining the head in any one of a plurality of operative positions including a drum segment connected to and movable with the head and a lever arranged to frictionally engage the drum segment, a fluid pressure system for actuating the buck and the lever, and means for actuating the fluid pressure system. 40
40. An ironing machine comprising an ironing head, a buck for cooperation therewith, means supporting the head for movement into and from operative position, friction means cooperating with the supporting means for retaining the head in any one of a plurality of operative positions including a drum segment connected to and movable with the head and a lever arranged to frictionally engage the drum segment, a fluid pressure system for actuating the buck and the lever, and means for actuating the fluid pressure system. 45
45. An ironing machine comprising an ironing head, a buck for cooperation therewith, means supporting the head for movement into and from operative position, friction means cooperating with the supporting means for retaining the head in any one of a plurality of operative positions including a drum segment connected to and movable with the head and a lever arranged to frictionally engage the drum segment, a fluid pressure system for actuating the buck and the lever, and means for actuating the fluid pressure system. 50
50. An ironing machine comprising an ironing head, a buck for cooperation therewith, means supporting the head for movement into and from operative position, friction means cooperating with the supporting means for retaining the head in any one of a plurality of operative positions including a drum segment connected to and movable with the head and a lever arranged to frictionally engage the drum segment, a fluid pressure system for actuating the buck and the lever, and means for actuating the fluid pressure system. 55
55. An ironing machine comprising an ironing head, a buck for cooperation therewith, means supporting the head for movement into and from operative position, friction means cooperating with the supporting means for retaining the head in any one of a plurality of operative positions including a drum segment connected to and movable with the head and a lever arranged to frictionally engage the drum segment, a fluid pressure system for actuating the buck and the lever, and means for actuating the fluid pressure system. 60

ANDREW O. McCOLLUM.
